UNITED STATES PATENT OFFICE.

ALBERT E. WYATT, OF JERSEY CITY, NEW JERSEY.

LOOP-ANTENNA-FRAME CONSTRUCTION.

Application filed March 13, 1924. Serial No. 639,064.

To all whom it may concern:

Be it known that I, ALBERT E. WYATT, a citizen of the United States, and a resident of Jersey City, in the county of Hudson and State of New Jersey, have invented a new and Improved Loop-Antenna-Frame Construction, of which the following is a full, clear, and exact description.

This invention relates to a loop antenna frame construction, and has for an object the provision of a simple, efficient, strong and durable frame which can be readily collapsed so as to be made easily portable or capable of being packed away in a small space.

Another object concerns the provision of means whereby when the frame is to be extended into its normal position this operation can be easily effected and the arms 20 are locked securely in their expanded normal position but, nevertheless, can be easily collapsed when desired.

A further object concerns the provision of means whereby the antenna wires on the 25 loop can be held in free parallel spaced relation at all times, especially when the frame is extended.

A still further object concerns the provision of structural details whereby the manufacturing costs can be reduced to a minimum.

The invention is illustrated in the drawings, of which—

Figure 1 is an elevation of the loop frame;

Fig. 2 is an elevation of the main supporting plate showing the loop frame arms cut off;

Fig. 3 is an elevation of the opposite side 40 of the main supporting plate;

Fig. 4 is a section on the line 4—4 of Fig. 2;

Fig. 5 is a similar section showing the arms collapsed;

Fig. 6 is a section on the line 6—6 of Fig. 1; and

Fig. 7 is a section on the line 7—7 of Fig. 1.

The form of the invention shown in the drawings is a preferred form, although it is understood that modifications in the construction and arrangement of the parts and in the character of the materials used may be adopted without departing from the spirit of the invention as set forth in the appended claims.

The frame construction comprises a main supporting plate 1 to which are adapted to be pivoted arms 2, 3, 4 and 5. The plate is cut away as shown at 6, 7, 8 and 9 to form openings, and projecting lugs or ear portions such as 10 and 11 are disposed in pairs on opposite sides of each opening to form pivotal supports for the arms. The inner ends of the arms are disposed to lie adjacent the inner edges such as 12 of the openings 6, 7, 8 and 9. The inner end of each frame is provided with a spring plate which is fastened at one end 13 thereto and extends across the under face of the arm. 65 This portion of the plate, marked 14, has a decided slope to it, and the other end is formed and bent around as at 15 to lie along the outside lateral face. The sloping portion of the spring plate, called the locking plate, is provided with a groove 16 which in the normal position of the arm is adapted to receive and engage with the inner edge of the associated opening in the plate 1 so that during this engagement the 80 arm is held definitely and positively in its normal position. To release the arm so that it can be moved to the position shown in Fig. 5, it is merely necessary to pull back on the free end of the spring plate so as to 85 release the edge of the main plate from engagement in the groove 16, whereupon the arm can be moved to the collapsed position shown in Fig. 5. This construction and operation is identical with respect to each 90 of the arms. In the movement of the arms from the position shown in Fig. 5 to that shown in Fig. 4, it will be observed that each arm is swung upwardly and that the sloping portion 14 of the spring plate engages the inner edge of the openings 6, 7, 8 and 9, and this engagement causes the free end of the spring plate to move back until the edge of the opening is in position to engage the slope, whereupon the spring plate collapses back into position and firmly holds the arms.

As shown in Figs. 1 and 6, the antenna wires such as 17 are held in their proper spaced relation by means of flexible bands 105 such as 18, of any suitable material, which are disposed around the wires and which are provided throughout their length with any suitable fastening means 19, which may be snap fasteners. These are used for the purpose of binding the band throughout its length together so as to space the wires in

groups of two or three whereby they may be maintained in this proper spaced relation, especially when the frame is expanded.

As shown in Fig. 7, each arm is provided with a plurality of grooves on its surface into which the wires are led, and then a plate such as 20 is placed over the surface of the arm and fastened thereto by a suitable means, such as a screw 21, so as to hold the wires in their proper position.

It will, therefore, be observed that I have provided a simple and efficient construction of a loop antenna frame which enables it to be readily collapsed to occupy a minimum space for storage or transmission and which, however, when expanded is maintained positively in this normal position by simple locking means which automatically engages upon expansion and can be very easily disengaged for collapsing.

What I claim is:—

1. A loop antenna frame construction, which comprises a plate, a plurality of antenna supporting arms radiating from said plate and pivoted thereto, and means on the arms adapted to automatically lock the arms to the plate when the arms are moved to normal expanded position.

2. A loop antenna frame construction, which comprises a plate, a plurality of antenna supporting arms radiating from said plate and pivoted thereto, and spring means on the arms adapted to automatically lock the arms to the plate when the arms are moved to normal expanded position.

3. A loop antenna frame construction, which comprises a plate, a plurality of antenna supporting arms pivoted to and extending from said plate and adapted to lie in a normal position when expanded, said plate being cut away adjacent the inner ends of said arms to form an edge adjacent each of said ends, a spring member on the end of each of said arms adapted to engage said edge, and means on the spring member adapted to positively engage with the edge when the arms are in their normal position to lock the arms in said position.

4. A loop antenna frame construction, which comprises a plate having an aperture cut therein, an antenna supporting frame pivoted on the plate having a normal position in which the inner end of the arm is disposed adjacent an edge of said aperture in said plate, and a spring plate mounted on the inner end of the arm and having a groove therein, said groove adapted to receive the edge of the plate when the arm is in normal position to lock the arm in said position with respect to the plate.

5. A loop antenna frame construction, which comprises a plate having an aperture cut therein, an antenna supporting frame pivoted on the plate having a normal position in which the inner end of the arm is disposed adjacent an edge of said aperture in said plate, and a spring plate mounted on the inner end of the arm and having a groove therein, said groove adapted to receive the edge of the plate when the arm is in normal position to lock the arm in said position with respect to the plate, one side of said plate being free for movement whereby it can be withdrawn to disengage the edge from the groove so that the arm can be collapsed or moved from its normal position.

6. A loop antenna frame construction, which comprises a plate having an opening cut therein, an antenna supporting frame pivoted to the plate adjacent said opening and adapted to have a normal position in which its inner end lies adjacent one edge of said opening, and a spring plate fastened to the inner end of said arm, said plate having a slight slope with respect to the ends, said plate having a groove therein, one edge of said spring plate being free, the arm adapted to be moved from a collapsed to a normal position and in said movement permitting the engagement of the edge of the main plate with the sloping portion of the spring plate whereby the edge rides along the spring plate until it snaps into said groove whereby the arm is locked in its normal position with respect to the main plate.

ALBERT E. WYATT.
